VARIABLE SPEED MECHANISM

Filed June 18, 1927

UNITED STATES PATENT OFFICE

TATSUJI MORIMOTO, OF PAIA, TERRITORY OF HAWAII

VARIABLE-SPEED MECHANISM

Application filed June 18, 1927, Serial No. 199,807, and in Japan December, 1926.

This invention relates to automatic or power driven scissors intended especially for barbers' use and has for its object the provision of reliable, compact and durable mechanism of this character.

5 Another object of the invention is the provision of a variable speed device for varying the speed at which the scissors action takes place.

10 Other objects and advantages will be apparent to those skilled in the art.

Referring to the drawings,

Figure 1 shows a perspective view of the scissors taken from an oblique position and 15 showing part of the housing cut away to expose some of the working parts,

Fig. 2 is a side elevation of the scissors with part of the housing plate cut away in order to show the operating mechanism,

20 Fig. 3 is an end elevation in section, taken on the line 2--2 of Fig. 1, also showing the operating mechanism of the scissors,

Figure 4 is a horizontal section taken on line 4--4 of Figure 2; and

25 Figure 5 is a similar view taken on line 5--5 of Figure 2.

Referring now to the drawings, Figures 1, 2 and 3 at 2 indicate a blade of the scissors which is power driven and adapted to move 30 over a stationary blade 3. The movable blade is held to the housing 32 of the scissors by a bolt 5 and nut 4. The stationary blade is held to the housing by the screw 6 transverse

35 of a blade, and also another screw 6 which holds the shank of the stationary blade in the direction at right angles to that of the screw 6.

Lower on the shank of the movable blade there is a screw 8 transverse of said shank which has a bearing upon a plate 7^a which fits 40

into a groove 5^a in the housing 32. This plate as is well shown in Fig. 5 rests upon a spring 7 accommodated in the groove 5^a and provides a yielding contact for the screw 8 and consequently for the blade 2. It will be ob-

45 served that the spring 7 acting against the plate 7^a exerts an outward pressure on the lower end of the blade 2 and thereby holds its cutting edge in close relation to the cutting edge of the blade 3.

50 In the lower part of the blade 2 there is a

slot 2^a in which a pin 10 carried by a gear 13 reciprocates. This gear is held in place by a stud 12 engaging the casing and is driven by a smaller gear 14 engaged in turn by worm gear 15. The gear 15 is engaged by a worm 18

55 which is carried on the same shaft as the two spur gears 17 and 19 respectively. Spur gear 19 is larger than spur gear 17 and forms the means with other spur gears namely at 20 and 22 whereby changes in speed may be accom-

60 plished. The gears 20 and 22 are connected together by a sleeve 20^a which is slidable on a fixed shaft 23 arranged below the worm 18. An eccentric 25 which is rotatable from the outside of the housing by a small handle 24 is 65 engageable with either of the gears 20 or 22 to shift them longitudinally. Rotation of this handle pushes the gears on the shaft to the left or right as the case may be and slides them in and out of engagement with gears 19 and 17.

70 Normally one of these gears 20 and 22 is engaged by a drive pinion 27. This pinion is fastened directly by means of screws to the extension of a flexible shaft 33 which enters the housing through its bottom portion.

75 Figure 2 shows more clearly the gear 15 which is a worm gear and lies on a gear 14, the rotation of gear 15 occurs by reason of the enmeshment of gear 18 with same, the worm gear arrangement providing a means of driving the gear 15 at a moderate speed with an exceedingly fast speed rotation of the gears 17 and 19.

80 It is to be understood that the flexible shaft 33 may be driven by any suitable means, for instance, an electric motor or other engine or even by hand, by a suitable arrangement of gearing.

85 In operation the drive may be traced as shown in Fig. 1 first through flexible shafts 90 33 through pinion 27 to bevel gears 26 thence to gear 20 and thence to gear 17, thence through worm gear 18 to worm gear 15 thence to spur gear 14 thence to spur gear 13 the pin 10, the motion of which in the slot 95 of the blade 2 provides a reciprocating motion and cutting action. It is to be understood that many minor changes and modifications may be made in the device without departing from the spirit of the invention, and 100

these modifications I claim as my own if they fall within the scope of the appended claim.

I claim:—

5 In a variable speed mechanism, a support, a shaft mounted on the support, pinions fixed to the ends of the shaft, a driven gear supported below the shaft, a longitudinally shiftable sleeve arranged parallel to the shaft, a bevelled gear fixed to each end of the sleeve and each carrying a pinion upon its outer face, one of which being normally in mesh with one of the first mentioned pinions, and a manually rotatable cam element mounted on the support and lying between the opposed 10 bevelled gears and movable against either of the latter to shift the sleeve in a direction to cause the shaft to be driven through either 15 one of the pinions carried thereby.

TATSUJI MORIMOTO.
